Des. 232,164
Patented July 23, 1974

232,164

SKI SKOOTER

John E. Bernis II, Keewatin, Minn. 55769, and George J. Knezovich, 3842 2nd Ave. W., Hibbing, Minn. 55746

Filed Apr. 9, 1973, Ser. No. 349,558

Term of patent 7 years

Int. Cl. D21—02

U.S. Cl. D12—10

FIG. 1 is a top plan view of a ski skooter showing our new design;

FIG. 2 is a side elevational view thereof;

FIG. 3 is a bottom plan view thereof;

FIG. 4 is a front end elevational view thereof; and

FIG. 5 is a rear end elevational view.

We claim:

The ornamental design for a ski skooter, as shown.
